UNITED STATES PATENT OFFICE.

CLAUDE B. FERRO, OF SAN BERNARDINO, CALIFORNIA.

TRAFFIC SIGNAL FOR MOTOR VEHICLES.

Application filed February 24, 1926. Serial No. 90,254.

My invention is a traffic signal for motor vehicles of the semaphore type, giving an illuminating signal at each signaling position and a signal lamp being extinguished in the movement of the semaphore arm from one signaling position to another.

An object of my invention is the construction of a traffic signal for motor vehicles of the semaphore type adapted to be attached directly to the framework of a vehicle, preferably of the closed type, the arm being actuated by a handle inside the car.

Another object of my invention is to construct the signal device of a pair of discs one being fixed in position and the other rotary; one of the discs also having a series of contact points and the other disc having a single contact adapted to be connected to a ground whereby on swinging of the semaphore arm a contact is made through any one of the contact points and hence gives a lighted signal for the different signaling positions of the semaphore arm.

In constructing my invention I attach a stationary disc to a tubular sleeve, this sleeve being adapted to pass through the framing of a motor vehicle. A rotatable disc has an operating shaft passing through the tubular sleeve with a handle on the inside of the vehicle. A semaphore arm is attached to the movable disc and carries a lamp at its outer end. The discs are formed with complementary grooves and in the groove of the moving plate there is positioned an electrical conducting metal segment with two insulating strips on each side insulating the conducting segment from the metal of the disc. A bolt is passed through the disc and through the strips, being insulated from the disc by having a conducting contact with the metal segment. Preferably three such bolts are used, the heads of said bolts forming contact points to be engaged by a slideable contact spring secured directly in the groove of the opposing disc. The electric wires lead from the battery or source of power to the semaphore arm through same to the lamp. The return circuit from the lamp is to one of the bolts and from the contact point formed by the head of the bolt through the sliding contact to the ground and hence returned to the battery.

My invention will be more readily understood from the following description and drawing, in which;

Figure 1 is an elevation of my signal taken from inside a vehicle.

Fig. 2 is a section of Fig. 1 on the line 2—2.

Fig. 3 is a part section and part elevation 60 of the fixed and stationary discs showing the electric connection therein.

Fig. 4 is an inside view of the moving disc having a semaphore arm attached thereto.

Fig. 5 is an inside view of the stationary 65 disc.

Fig. 6 is a detail view of the segments making up the insulated conducting segment mounted in the groove of the moving disc.

Fig. 7 is a diagram showing the mounting 70 and manner of use of my signal, the view being from inside a vehicle.

In the drawings a stationary disc 1 has a tubular sleeve 2 screw threaded at the end with a lock nut 3 thereon. This disc may 75 therefore be attached to a vehicle framing by boring a hole through such framing and inserting the tubular sleeve through the hole, clamping it firmly in position by the nut 3. The disc is provided with an annular groove 80 4 and a centering recess 5.

A complementary movable disc 6 has a hub 5' fitting in the recess 5 of the disc 1 and a flange 6' extending over the periphery of the disc 1, and has an operating shaft 7 connected thereto, this shaft extending through the tubular sleeve. A nut 8 is threaded on the operating shaft bearing against the inner end of the tubular sleeve with sufficient pressure to hold the signal in 90 any desired position. The nut 8 is preferably castellated and has a cotter pin 9 to hold the same in adjusted position.

A handle 10 having a hand grip 10' has a hub 11 fitting over the end of the operating shaft and over the nut 8 and being secured in position by the pin 12.

The movable disc is provided with an annular groove 13 in which is fitted an insulated conducting strip designated generally 100 by the numeral 14. The elements of this strip are illustrated in Fig. 6 and comprise two outer segments 15 and 16 and a metal conducting segment 17. These are shaped to fit in the groove and extend through a sufficient arc in the groove 13 in accordance with all the signals required by swinging the semaphore.

The insulated conducting segment is secured to the disc 6 by a series of bolts 18 110

- having insulating bushings 19 between the bolt and the metal body of the disc 6. The bolts however, contact with the metal segment as illustrated by the numeral 20 in 5 Fig. 3. The bolt heads 21 form contact points in the inside of the disc as hereunder set forth and nuts 22 on each of the bolts are utilized to clamp the electric lead 23. A sliding contact 24 is formed of a spring 10 having an outwardly bent section 25 and a flat end 26, the flat end being secured in the base of the slot 4 of the stationary disc 1 by means of a screw 27 or the like.
- 15 A semaphore arm 28 illustrated as a tube or pipe is secured to the disc 6 in any suitable manner and at its outer end carries a lamp socket 29 secured thereto by a collar 30, the socket having a signal frame 31 with glasses 32 therein and a signal lamp 33 secured in the socket. The electric lead 23 extends from one of the bolts 18 as above mentioned and passes through an opening 34 in the tube 28, being connected to the lamp. A battery lead 35 is also connected to the 20 lamp.
- 25 The operation of my signal is substantially as follows:

Preferably the signal is supported on the vehicle as shown in Fig. 7 in full lines with 30 the semaphore hanging vertically downwardly and with the handle extending up on the inside of the vehicle. To give the stop signal the handle is moved a portion 35 of a circle so that the semaphore arm is inclined downwardly at an angle of about 45° in which position the sliding contact 24 engages one of the contact points 21 of the bolts 18, thereby giving a light signal. A left hand turn signal is given by moving the 40 semaphore arm into the horizontal position and in the transition the light is extinguished and again illuminated when the semaphore is in such position.

45 A right hand turn signal is given by inclining the semaphore arm upwardly at an angle of about 45°, the sliding contact then

engages one of the contact points. It is only necessary that the lead 23 from the lamp be connected to one of the bolts 18 as these all form electrical connections with the strip 17 and hence the current is conducted along the strip in either direction and through the sliding spring contact 24 to the metal structure of the disc 1 hence to ground through the frame of the machine. 55

Although my invention is of a simple character, nevertheless it will be apparent that various changes could be made. The grooves have been shown continuous so that a signal may be installed for either right 60 or left signaling in accordance with the position of the contact points and also to allow different types of signals to be given by different positions of the semaphore arm. Moreover, some other type of arrangement 65 could be used to hold the arm in its adjusted position other than the friction construction shown. Such changes would be within the spirit of my invention as set forth in the description, drawings and claim. 70

Having described my invention, what I claim is:

In a traffic signal a relatively stationary metal disc, a rotatable metal disc mounted thereon, said discs having complementary 75 grooves, a semaphore arm attached to the rotatable disc having a lamp, a conducting segment formed of a strip of conducting material and having insulating strips on opposite sides, bolts securing said strip in the 80 groove of one of the discs, the said bolts being insulated from the disc and having electric contact with the conducting strip, a relatively slidable contact attached to the opposite disc in a groove positioned to engage the contact points and means to conduct an electric current through the lamp, through one of the bolts and the sliding contact to ground through one of the discs. 85

In testimony whereof I have signed my 90 name to this specification.

CLAUDE B. FERRO.
